HIGH FREQUENCY ELECTRO-SURGERY KNIFE

David E. Staub, Clearwater, Fla., assignor to
Concept, Inc., Clearwater, Fla.

Filed Sept. 13, 1974, Ser. No. 505,568

Term of patent 14 years

Int. Cl. D24—02

U.S. Cl. D83—12 B

Fig. 1.   *Fig. 2.*

Fig. 3.

Fig. 4.

FIG. 1 is a front elevational view of the high frequency electro-surgery knife showing my new design;

FIG. 2 is a side elevational view thereof;

FIG. 3 is a top plan view thereof; and

FIG. 4 is a bottom plan view thereof.

I claim:

The ornamental design for a high frequency electro-surgery knife, substantially as shown.
